The ornamental design for a display screen or portion thereof with keyboard graphical user interface, as shown and described.

DESCRIPTION

FIG. 1 is a top plan view of a first image in a sequence showing a display screen or portion thereof with keyboard graphical user interface in portrait mode.

FIG. 2 is a top plan view of the layout in FIG. 1 shown in conjunction with a phone shown in phantom.

FIG. 3 is a top plan view of a second image in a sequence showing a display screen or portion thereof with keyboard graphical user interface in portrait mode; and,

FIG. 4 is a top plan view of the expanded layout in FIG. 3 shown in conjunction with a phone shown in phantom.

The appearance of the image transitions sequentially between the images shown in FIG. 1 and FIG. 3, and FIGS. 2 and 4. The process or period in which one image transitions to another forms no part of the claimed design.

The broken lines are for environmental purposes only and form no part of the claimed design.
